DEVICE FOR SECURING OBJECTS TO WALLS
AND SIMILAR STRUCTURES

Frank J. Porwoll, St. Cloud, Minn.

Application October 28, 1937, Serial No. 171,599

6 Claims. (Cl. 72—105)

My invention relates to devices for securing objects to walls and similar structures. While intended primarily for use in securing electrical wires or pipes containing the same, it will be understood that the device may be employed for securing other objects which might be pipes for carrying things other than electrical wires. An object of the invention is to provide a device of this character consisting of a plug of malleable material such as pig lead adapted to be expanded in a hole provided therefor in a wall or similar structure, and a flexible element secured to and extending from said plug so as to be adapted for bending or twisting around the object which it is desired to support from the wall. It will be understood that as many of the devices as are necessary to carry the object to be supported may be installed at spaced intervals on the wall.

The novel features which I believe to be characteristic of my invention are set forth with particularity in the appended claims. The invention itself, however, both as to its organization and method of operation, together with additional objects and advantages will be best understood from the following description of specific embodiments in which,

Fig. 1 is a perspective view of one form of the device.

Fig. 2 is a sectional view showing this form of the device applied in use.

Fig. 3 is a view in section on the line 3—3 of Fig. 2.

Fig. 4 is a perspective view of a slightly modified form of the invention.

Fig. 5 is a sectional view showing the last mentioned form applied and ready for use.

Fig. 6 is a perspective view of another form of construction.

Fig. 7 is a view in section on the line 7—7 of Fig. 6.

Fig. 8 is a fragmentary perspective view of a still further form of construction.

Referring first to the form of the device shown in Figs. 1, 2 and 3, a wire designated in general by the numeral 10 is bent intermediate its ends preferably nearer one end than to the other to form a loop 12 from which extend a branch 14 and a shorter branch 16, these branches being substantially parallel to each other. The looped portion of the wire is combined with a plug 18 of soft malleable material such as pig lead which may be readily molded into a plug of the desired size. The bent portion of the wire is looped around the plug so as to be attached thereto. This may be conveniently done by inserting the

loop in the mold before the lead or other moldable material is poured thereinto so that the loop will be anchored in the outer surface of the plug produced by the molding operation.

In order to install the device for use, a hole of the proper size is drilled or otherwise formed in a supporting structure W such as a concrete or brick wall. After the plug 18 and encircling loop 12 have been inserted in said hole, the plug is pounded on its outer end by a suitable tool so as to expand it in the hole thereby firmly securing the device to the wall or other supporting structure. The protruding branches 14 and 16 of wire are then bent around and secured together as by twisting upon any object to be held, such object primarily being a pipe P for carrying wires such as electrical wires. It will be understood as a matter of course that as many of the devices as are necessary may be installed at spaced intervals on the wall.

Figs. 4 and 5 show a slight modification in which the branch 14 is provided with a rubber sheath 20. It is apparent that if desired, a similar rubber sheath might be provided for the branch 16. This form of the device is adapted to support wires which are not enclosed in a pipe.

Figs. 6 and 7 show a modification in which a strip 22 of flexible metal in ribbon-like form is employed in place of a wire. This strip intermediate its ends preferably nearer one end than the other is bent to form a loop 24 from which extend a branch 26 and a shorter branch 28, these branches being substantially parallel to each other. The looped portion of the strip is combined with a plug 30 of soft malleable material such as pig lead which may be readily formed in a mold of the desired size. The bent portion of the strip is looped around the plug 30. This may be conveniently done by inserting the loop in the mold before the moldable material is poured thereinto so that the loop will be anchored in the outer surface of the plug produced by the molding operation. The outer end of the branch 28 carries an enlargement 32 provided with a slot 34 through which the branch 26 may be inserted and then secured by bending to hold in place a pipe or other object to be supported. It will be understood as a matter of course that the plug 30 will be installed in similar manner to the plug previously referred to.

Fig. 8 shows a modification in which a plug 36 in the form of a disk of malleable material such as pig lead is employed. The plug 36 is provided in suitable manner as by punching, with two

holes 38 and 40. In connection with the plug 36, a wire 10' which may be of larger size than the wire 10, is employed. The wire 10' is bent to form a connecting member 12' from which 5 two branches 14' and 16' extend, these branches being readily attached to the plug by passing them through the holes 38 and 40 respectively. The device will then be installed in a manner similar to that already described by providing a hole in 10 the wall or supporting structure and expanding the plug in this hole.

The operation and advantages of my invention will be fully understood in connection with the foregoing description and the accompanying 15 drawing. The principle involved is substantially the same in all of the forms disclosed, this principle embodying the idea of providing a plug of malleable material upon which a flexible element is looped or otherwise secured, the device thus 20 produced being installed by expanding the plug in a hole provided in a wall or other supporting structure. This device has been found to be very efficient in practice. The expansion of the malleable material in the hole provided therefor gives 25 a very firm grip which holds more firmly the more that force is exerted on the flexible element tending to pull it from its anchorage in the wall. This result is due to the fact that the flexible element is looped at the rear of the plug which is of malleable 30 or somewhat plastic material. Therefore any pull exerted upon the loop causes the forward portion of the plug to be crowded out and flow against the wall of the opening or hole in which the plug is inserted. This action was proved by tests which 35 were made.

I claim:

1. In a device of the character described, the combination of a plug of malleable material adapted to be expanded in a hole provided therefor in a wall or similar structure, and a flexible element looped around said plug to provide two branches extending therefrom adapted to be bent around an object to be supported from the wall.
2. In a device of the character described, the combination of a plug of molded malleable material adapted to be expanded in a hole provided therefor in a wall or similar structure, and a flex-

ible element having a portion thereof molded in said plug and a portion extending therefrom adapted to be bent around an object to be supported from the wall.

3. In a device of the character described, the combination of a plug of molded malleable material adapted to be expanded in a hole provided therefor in a wall or similar structure, and a flexible looped element having its loop molded in said plug to provide two branches extending therefrom adapted to be bent around an object to be supported from the wall.

4. In a device of the character described, the combination of a plug of malleable material adapted to be expanded in a hole provided therefor in a wall or similar structure, a strip of flexible material looped around said plug to provide two branches extending therefrom, and an enlargement containing a slot formed in the outer end of one of said branches, the other one of said 10 branches being adapted to be bent around an object to be supported from the wall and the outer end of said second branch being adapted to be inserted through said slot and secured thereby.

5. In a device of the character described, the combination of a plug of molded malleable material adapted to be expanded in a hole provided therefor in a wall or similar structure, a flexible looped strip having its loop molded in said plug to provide two branches extending therefrom, and an enlargement containing a slot formed in the outer end of one of said branches, the other one of said branches being adapted to be bent around an object to be supported from the wall and the outer end of said second branch being adapted to be inserted through said slot and secured thereby.

6. In a device of the character described, the combination of a disk-like plug of malleable material adapted to be expanded in a hole provided therefor in a wall or similar structure, said disk containing two holes, and a flexible looped element having two branches passing through said holes respectively and extending from said plug whereby the branches are adapted to be bent around an object to be supported by the wall.

FRANK J. PORWOLL.
